COKE OVEN IRONWORK

Louis Wilputte, New Rochelle, N. Y.

Application June 23, 1934, Serial No. 732,023

11 Claims. (Cl. 202—248)

The present invention relates to the ironwork employed at the margins of the doorways and engaging the ends of the heating walls of a coke oven battery or structure of the well known type having horizontally elongated open-ended coking chambers arranged side by side and separated by flued heating walls. More particularly the present invention is concerned with coke oven ironwork comprising a one piece metallic door frame member extending into the coke oven masonry at the margin of each coking chamber end and having its sides received in recesses formed in the adjacent heating walls, and also comprising a flash plate covering all or the major portion of the end surface of each heating wall between the door frame recesses thereof, one or more buck stays at each end of each heating wall and engaging the latter through the corresponding flash plate, and means for detachably connecting the door frames to the adjacent buck stays.

The general object of the present invention is to effect improvements in coke oven ironwork of the character specified. More specific objects of the present invention are to provide improvements contributing to the attainment of one or more of the following results, or advantages, namely: Easy removability of the door frame members and resultant accessibility of the ends of the masonry heating walls for repairs which may be made while the walls are hot and without requiring the removal of the buck stays and flash plates; the avoidance of objectionable gas leakage through the joints in the ironwork adjacent each end of a heating wall and between the ironwork and the masonry end of the heating wall; the provision of simple and effective mechanical connections between the buck stays and door frames normally holding the latter in place, but adjustable or removable as required for the removal of a door frame.

The invention is particularly characterized by the provisions of a rigid door frame member with lateral flange members which are in overlapping engagement with the corresponding flash plates and are of such form and are so adjustably connected to said rigid door frame members that they may be readily maintained in snug engagement with the adjacent flash plates, notwithstanding the relative movements, both vertically and horizontally, of the door frames and flash plates resulting from the unequal thermal expansion of different parts and other conditions to which coke ovens are subjected in operation.

The various features of novelty which characterize my invention are pointed out with particu-

larity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is a horizontal section of a portion of a coke oven battery, taken on the line 1—1 of Fig. 1;

Fig. 2 is a side elevation of a portion of the coke oven battery; and

Fig. 3 is a vertical section taken on the line 3—3 of Fig. 2.

The coke oven shown in the drawings is of the type comprising side by side horizontal coking chambers A separated by masonry heating walls B formed with vertical heating flues B' arranged in a row extending from one end of the wall to the other, the otherwise open ends of the coking chambers being normally closed by removable plug doors C.

Each door C in its closed position is surrounded by and is seated against a one piece door frame member D. In the preferred construction illustrated, each door frame member D is a rigid one piece metallic casting of substantial horizontal depth measured in the direction of the heating walls B, which are recessed at their vertical corners, as indicated at B² to receive inner portions 30 of the door frame members D, which extend into the coke oven masonry. As shown each door frame member D has an inturned flange portion D' at its sides and top, said flange being engaged by a metallic flange portion C' of the corresponding door C in the closed position of the latter. At the sides of each doorway, the edge D² of the flange D' is substantially flush with the adjacent side walls of the corresponding oven chamber. The horizontal top portion of the flange D' is 40 preferably at a level above the top of the oven chamber, the masonry above the coking chambers being formed with recesses B³ to receive the upper portions of the door frame members D. The latter extend downward below the floor levels 45 of the oven chambers and each door frame member D provides support for a metallic member D³ forming a part of the floor of the corresponding oven chamber.

In accordance with the present invention, each 50 door frame member D comprises an outer portion extending outwardly beyond the ends of the oven heating walls far enough to provide suitable bearing surfaces against which door frame flange members d are detachably secured. As shown gg

each flange member *d* is formed of metal of angle bar cross section and has one angle bar flange alongside of and clamped against the outer side of the adjacent outer portion of the door frame member *D*, and has its second angle bar flange extending away from the member *D* and overlapping an edge portion of a metallic flash plate *E* which engages the end of the adjacent heating wall *B* and preferably extends between the outer edges of the two corner recesses *B*² thereof. As shown a packing *F*, which may be formed of asbestos fiber material and be similar in cross section to each flange member *d*, has one flange portion interposed between the latter and the adjacent door frame member *D*, and has its other flange portion interposed between the flange member *d* and the flash plate *E* which it overlaps.

In the preferred construction illustrated each flange member *d* is adjustably clamped against the side of the corresponding door frame member *D* by bolts *G* suitably spaced in a vertical row and each extending through a bolt hole *D*⁴ formed in the member *D* and through registering holes formed in the adjacent flange member *d* and packing member *F*. The last mentioned holes are suitably enlarged to permit adjustment of the flange member *d* relative to the member *D* as required to insure a gas tight joint between the flange member *d* and the flash plate *E* which it overlaps, notwithstanding the relative bodily movements of the members *D* and *E* which are inevitable results of the stresses, mainly thermal, to which the oven structure is subjected in operation. As those skilled in the art understand, those stresses produce relative movements of the members *D* and *E* in the direction of the lengths of the heating walls, which are different at different elevations, and each flange member *d* should be sufficiently flexible to permit it to be readily deformed when and as required to conform to and maintain engagement with the corresponding flash plate *E*. Adequate flexibility for the purpose is obtained by forming each flange member *d* of several sections, with abutting ends *d*', of an ordinary rolled steel angle bar having a metal thickness of five-sixteenths of an inch or so. This permits the separate end to end sections of each flange member *d* to be separately adjusted into general parallelism with adjacent portions of the flash plates so that but little actual bending of the individual sections is ordinarily needed to insure the desired flange and flash plate conformity at all points along their length.

In the preferred construction illustrated, the bolt holes *D*⁴ in the members *D* are inclined so that the bolts *G* diverge at a slight angle away from the flash plates *E* which they overlap, and a correspondingly tapered washer *g* surrounding such bolt *G*, is interposed between the nut on the outer end of the bolt and the corresponding flange member *d*, so that movement of the latter relative to the member *D* to which it is secured will not be produced by the inwardly acting force holding the latter in place. As shown, the heads of the bolts *G* are received in recesses *D*⁵ which in effect are enlargements of the inner ends of the bolt holes *D*⁴.

The inwardly acting forces to which the door frame members *D* are subjected must be sufficient to suitably compress the packing members *F* and, in the preferred construction illustrated, to suitably compress the asbestos rope or other packing material *H* interposed between suitably shaped portions of the members *D* and of the heating wall recesses *B*². Moreover the means

through which such forces are impressed on the members *D*, should be strong enough to prevent displacement of the latter under the shocks and stresses to which they are subject as a result of the operation of the door and charge handling machinery. Advantageously each door frame member *D* is anchored in place, and the associated packings *F* and *H* suitably compressed by readily removable connections between the members *D* and the buck stays *I* vertically disposed at the corresponding ends of the adjacent heating walls. The buck stays *I* hold in place the flash plate members *E*, each of which may be welded or otherwise secured to a corresponding buck stay.

In the preferred form shown, the said connections comprise a series of clamping bars *J* located at suitably different levels at each side of each member *D* and acting between the latter and the adjacent buck stay *I*. As shown each buck stay is in the form of an I beam and is connected to 20 each member *J* associated therewith through a member *K*, welded to the adjacent base and web portions of the I beam. Each part *K* is slotted at *K*' to receive, and to hold the head of a bolt *L* extending horizontally away from the heating 25 wall at some distance from the web of the buck stay, and between said web and the adjacent member *D*. Each bolt *L* passes through an aperture formed in the corresponding member *J* intermediate the inturned ends of the latter. One 30 end of each member *J* has a fulcrum engagement with the corresponding member *K* adjacent the web of the I beam, while the other end of the member *J* engages the outer edge of the member *D*. In consequence, when the nut *L*' on the 35 corresponding bolt *L* is tightened, each member *J* acts as an arm or lever tending to force the member *D* engaged by it into the oven structure as far as its flanges *d* will permit.

Each door frame body member *D* may be shaped 40 to receive a door of any usual or suitable type, and in particular to receive a so called self sealing door or a door having the joints between it and the member *D* luted to prevent gas leakage. The doors *C* are of the last mentioned type, and are 45 generally similar in form to those shown in my Patent 1,234,202, granted November 4, 1919, each door *C* comprising a cast metal rim member *C*², a metal plate *C*³ extending across the opening in, and being bolted to the member *C*², and a refractory body *C*⁴ secured in the rim member *C*² at the inner side of the plate *C*³. The previously mentioned door flange *C'* which overlaps and engages the inturned flange portion *D'* of the member *D*, is an integral portion of the rim member *C*². The edge of the flange *C'* and the adjacent portion of the door frame member *D* are oppositely inclined to provide a trough shaped channel or groove *CD* for the reception of fire clay or other luting material.

As shown, upper and lower brackets *M* bolted to each door member *C*² have latch bars *O* pivotally connected thereto to turn into and out of engagement with latch hook members *O'* welded or otherwise suitably secured to the corresponding door frame members *M*, so that each door *C* may be quickly locked to, and unlocked from the corresponding door frame member *D*.

As those skilled in the art will readily understand, the described construction permits the 70 ready removal of each door frame member *D* for adjustment or repair purposes. To remove a door frame member *D*, all that is required is to release the clamping nuts *L*' and remove the bars *J* or adjust the latter into vertical positions so 75

that they do not interfere with the removal of the member D. The latter may then be removed, as by operating the usual door handling machinery to engage and manipulate the door while locked in its door frame, as the door when not locked to the door frame member is manipulated in the normal door opening operation.

The removal of each door frame member D, permits the ready removal of the corresponding packing material F and H, and such adjustment and reshaping of the flexible flange members d, as may be required to insure their proper engagement with the flash plates E. Furthermore since each flash plate is of a width less than the full thickness of the adjacent heating wall end and has no portion extending into the masonry portion of the coke oven, the removal of each member D exposes enough of the adjacent heating wall ends, to permit the latter to be repaired without cooling the oven down and without the removal of the corresponding flash plate, even when the required repairs involve the chipping out of one or more of the heating wall bricks b, b¹, b² and b³, and the insertion of substitute bricks. This is practically important because the heating wall ends are especially apt to need repairs from time to time. With the described construction, the members D may be made as massive as is necessary to give them ample strength and rigidity.

While in accordance with the provisions of the statutes, I have illustrated and described a preferred form of embodiment of the invention, those skilled in the art will understand that changes in the form of the apparatus disclosed may be made without departing from the spirit of the invention as set forth in the appended claims, and that some features of the invention may sometimes be used with advantage without a corresponding use of other features.

Having now described my invention, what I claim as new and desire to secure by Letters Patent is:

1. In a coke oven structure of the type comprising horizontally elongated coking chambers and masonry heating walls arranged alternately in a row and removable doors normally closing the ends of said chambers, the combination with a metallic flash plate at each side of one end of a coking chamber in front of, and engaging the adjacent heating wall end, a buckstay in front of and engaging each flash plate, a rigid metallic member at, and forming a frame for the door at, said coking chamber end and extending past the adjacent side edges of said flash plates into the oven structure, and metallic flange members secured to and extending longitudinally of the opposite sides of said rigid door frame member and each overlapping the adjacent flash plate member and each being adjustable relative to said rigid door frame member to permit different longitudinal portions thereof to be relatively displaced in the direction of the lengths of the heating walls.

2. A combination as specified in claim 1 in which the said flange members are each of angle bar cross section including a flange substantially parallel to and forming the portion of the flange member overlapping the adjacent flash plate and a second flange alongside of and adjustably secured to said rigid door frame member.

3. A combination as specified in claim 1 in which clamping bolts extending through each flange member and the said rigid door frame

member adjustably secure said members together, said bolts being inclined to the flash plate overlapped by said flange member.

4. A combination as specified in claim 1 in which the said flange members are each of angle bar cross section including a flange substantially parallel to and forming the portion of the flange member overlapping the adjacent flash plate and a second flange alongside of the said rigid door frame member, and in which clamping bolts extending through and adjustably securing together the last mentioned flange and rigid door frame member are inclined to the flash plate overlapped by said flange member and subject the latter to a wedging action opposing movement of said rigid door frame member toward the coke oven structure relative to said flange member.

5. A combination as specified in claim 1 in which said flange members are of angle bar cross section each comprising one flange substantially parallel to and adjacent the flash plate overlapped by said flange member and a second flange alongside and detachably clamped against the outer portion of the said rigid door frame member, and a packing material member extending longitudinally of each flange member and of angle bar cross section including one flange interposed between the adjacent flash plate and the flange of said flange member adjacent thereto and a second flange interposed between said second flange of said flange member and the rigid door frame member to which it is clamped.

6. A combination as specified in claim 1 and removable connections between the said rigid door frame member and the adjacent buckstays by which the flange members adjustably secured to said rigid door frame member are pressed against the corresponding flash plates and said rigid door frame member is held in place relative to the coke oven structure.

7. A combination as specified in claim 1 and means for clamping the flange members adjustably secured to the said rigid door frame member against the corresponding flash plates.

8. In a coke oven structure of the type comprising horizontally elongated coking chambers and masonry heating walls arranged alternately in a row and removable doors normally closing the ends of said chambers, the combination with a metallic flash plate in front of and engaging each of the two heating wall ends at opposite sides of one end of a coking chamber, a buckstay in front of each flash plate and having a web portion extending away from said flash plate and a base portion alongside and engaging said flash plate, a metallic member at and forming a frame for the door at the said oven chamber end and each having a portion extending past the adjacent side edges of said flash plates into the oven structure and having a portion extending outwardly from said flash plates, and having flange portions at and extending longitudinally of its opposite sides and each overlapping the adjacent flash plate member and means for connecting said metallic member to an adjacent buckstay comprising a part attached to the base portion of the latter, a bolt connected to said part and a clamping member connected to said part by said bolt and engaging said metallic member at one side of said bolt and engaging said buckstay part at the opposite side of said bolt.

9. A combination as specified in claim 1 in which said flange members are each formed of a plurality of end to end sections.

10. A combination as specified in claim 1 in

which each flange member is bendable to permit relative displacement of different longitudinal portions thereof in the direction of the lengths of the heating walls.

5 11. A combination as specified in claim 1, and connections between the said rigid door frame member and each adjacent buckstay comprising a plurality of clamping members disposed at different levels, and each having two bearing

portions horizontally displaced from one another, one of which engages said buckstay and the other of which engages said door frame member and tension means connected to and acting between said buckstay and each clamping member 5 intermediate the said bearing portions of the latter, and pressing said bearing portions against said buckstay and door frame member.

LOUIS WILPUTTE.
